ROPE WHIPPING SEWING MACHINE

Philip T. McLendon, Atlanta, Ga., assignor to
 Union Special Machine Company, Chicago, Ill.,
 a corporation of Illinois

Application February 4, 1944, Serial No. 521,057

6 Claims. (Cl. 112—2)

1

This invention relates to a method of and means for whipping the ends of rope and the like to prevent untwisting and raveling of the strands thereof. It relates also to the product of such method.

Heretofore, in finishing off the free ends of ropes such as used in connection with tents, tar-paulins, flags, sails and the like, it has been a common practice to wrap cords or other types of filament about the ends to prevent the fraying and raveling of the same. This prior whipping method, however, has been relatively slow and expensive, and has not been altogether satisfactory. The wrapping cord has a tendency to break or wear through at some point and then become quickly unwound and stripped from the end of the rope. When the rope end is thus unprotected, the untwisting and raveling process soon begins.

A primary object of the present invention has been to provide a method of and machine for so stitching the end of a rope that it will remain more or less permanently protected against untwisting and raveling in spite of any rough usage to which it may be subjected.

Another object has been to provide an improved form of whipping or similar protection for rope ends which is simple, reliable and inexpensive, and which may be speedily applied to the rope ends in large scale production.

A further object has been to provide a method and machine, of the character above indicated, capable of producing the improved form of whipping rapidly and in an economical manner, without special skill.

Toward the foregoing ends the invention contemplates the formation of a series of stitches through the end of the rope, these stitches being preferably of the two-thread lock stitch type. The stitching in the preferred form of the invention is arranged to extend in a generally spiral or helical direction about the rope end, the needle upon each stitching operation being arranged to pass through the rope at a point spaced circumferentially of the rope and advanced slightly axially in relation to the preceding stitch. Moreover, the threads forming the stitches are preferably arranged to pass through the rope along lines transverse to the axis of the rope end but spaced some distance from such axis. Thus the stitching threads extend through the rope along chords of its circular cross-section, preferably about midway between the axis and the periphery of the rope-end.

Other objects, features and advantages of the invention will appear from a detailed description

2

of certain illustrative forms of the same, which will now be given in conjunction with the accompanying drawings in which:

Fig. I is a view in side elevation of the needle head and associated devices forming part of the improved machine constructed in accordance with the invention.

Fig. II is an end elevation of the machine with the cover plate of the needle head removed and with certain parts broken away and shown in section.

Fig. III is a schematic view on a greatly enlarged scale illustrating the arrangement of stitching through a section of the rope end, the stitches being shown larger and more widely spaced than in actual practice.

Fig. IV is a view similar to Fig. III but showing a fewer number of stitches to each turn about the rope for clarity of illustration.

Fig. V is an exploded perspective view of the presser foot, throat plate and feed dog of the improved machine; and

Fig. VI is a side view of a rope stitched in accordance with the present invention.

Referring now to the drawings, the invention has been illustrated as applied to a flat bed sewing machine of the lock stitch type, such as shown in the patent to Norman V. Christensen et al., No. 2,113,572, granted April 12, 1938. It will be understood that the invention is applicable, however, to a variety of other types of sewing machine.

The illustrative machine is provided with a base 10, a vertical standard 11 and a horizontally extending overhanging arm 12 carrying at its end a needle head 13. Power may be applied to the machine in the manner indicated in said Christensen et al. patent to drive a main shaft 14 (Fig. II) which extends longitudinally of the arm 12 into the needle head. Suitable crank means provided in the needle head serves to cause vertical reciprocation of a needle bar 15 mounted in bearings in the needle head. At its lower end the needle bar carries a needle 16 arranged to be reciprocated upon each cycle of operation of the machine to carry the needle thread 16a (Fig. I) through the work into cooperation with the complementary stitch-forming means. The latter, as illustrated in Fig. II, may suitably be in the form of a rotary hook 17 driven by suitable connections extending from the shaft 14 through the standard 11 and the base 10 in the manner disclosed in said Christensen et al. patent. Also driven by suitable connections from the shaft 14 is a feed dog 18 of the four motion type carried by a feed bar 19 pivotally supported at its end upon a rocker 20.

Toothed portions 18a (Fig. V) of the feed dog pass through openings 18b in a throat plate 18c to engage the rope. The feed dog is given its feed and return movements by the rocking of the rocker 20 and it is raised and lowered by a link 21 having its lower end connected with an arm extending downwardly from the feed bar and having its upper end engaged with a crank pin at the end of a main operating shaft (not shown) within the base, all in the manner disclosed in said Christensen et al. patent. Any suitable means, such as that disclosed in said patent, may be provided for varying the length of the feed stroke.

Cooperating with the feed dog is a presser foot 22, the shank 23 of which is detachably mounted upon the lower end of a presser bar 24. The latter is mounted for vertical movement in suitable bearings in the needle head and is normally urged downwardly by means of a spring 25 acting at its upper end against an adjustable sleeve 26 and at its lower end against a block 27 secured to the presser bar. Any suitable means, such as a lever 28 adapted to be operated by a link 29 connected with a foot treadle or knee-operated control, may be provided for lifting the presser bar whenever desired. The feed end of the lever 28 is connected for this purpose by means of a link 30 with a sleeve 31 slidably mounted on the presser bar. A hand operated lever 31a may also be provided for lifting the sleeve 31 and hence the presser bar 24.

As shown in Figs. II and V, the presser foot 22 is provided with a substantially semi-cylindrical groove or recess 32 in its under surface which is adapted to snugly receive the end of the rope to be whipped. Due to the pressure of the presser bar spring 25, the rope may be deformed slightly from its normally circular contour into the elliptical contour illustrated in Fig. II. A needle passage 33 is provided through the presser foot to guide and permit the free movement of the needle therethrough. This passage, as shown in Fig. II, is disposed forwardly of the vertical center line of the groove or recess 32. Thus the stitching produced upon the reciprocation of the needle will pass through the rope along a line somewhat removed from its axis, i. e., the line of action of the needle constitutes a chord rather than a diameter of the cross section through the rope being stitched. Preferably the line of action of the needle in relation to the rope holding means is such that the needle substantially bisects the horizontal radius of the rope. This off-center action of the needle will not, however, cause rotation of the rope due to the frictional resistance of the presser foot and the throat plate.

In the operation of the machine, the presser foot will be lifted, by rocking the lever 28 in the manner explained, to permit introduction of the end of a rope properly within the groove or recess 32. The presser foot may then be lowered and the machine set in operation. Between the successive stitches, the feed dog 18 will be operated to rotate the rope through a desired angular distance to provide the desired length of stitch. At the same time, the operator will exert a slight pushing or pulling force upon the end of the rope to cause it to advance gradually in an axial direction along the groove 32. In this way the spiral or helical effect indicated in Fig. VI is provided. Upon completion of the stitching the presser foot is again raised, the threads cut or broken and a new end of rope is inserted. This operation may be carried out repeatedly at high speed.

Referring now to Figs. III and IV, the form of

the stitching provided in the rope end by the operation described is schematically illustrated on an enlarged scale. As indicated, the stitch-forming means and the thread take-up devices of the machine are preferably so adjusted that the needle loops 16b will be drawn inwardly into the rope and the bobbin thread loops 17b will be similarly drawn into the rope so that the points of interengagement of these loops are spaced substantially midway between the ends of the cord along which the needle passes through the rope in forming a stitch. The drawing of the interlocked loops of the two threads into the interior of the rope in this way is accomplished by proper adjustment and operation of a thread tensioning device 34 and a take-up arm 35 connected at 36 to the crank which operates the needle bar. This construction is more fully described in said Christensen et al. patent and in the patent to Nelson 2,077,151, granted April 13, 1937. Briefly, the needle thread 16a passes from a source of supply to a guide 37, thence between the discs of the tensioning device 34 over a check wire 38, under a thread controlling guide 39 carried by the presser bar, thence through an eyelet in the arm 35 down to the needle. The stitch setting action takes place on the upward movement of the arm 35 and is such as to produce the result indicated. It is satisfactory so long as the looped and interlocked portions of both the needle thread and the bobbin thread are drawn into the body of the rope and do not remain on its surface. In this way undue roughening of the surface of the rope will be avoided. Moreover, the danger of breakage of the loops is reduced to a minimum. But in any event, as will be apparent, the breaking or wearing through of any length of either the needle thread or the bobbin thread which lies around the circumference of the rope will not disturb any of the remaining stitching. Each stitch is retained by its frictional engagement with the rope in passing through the same and there is no danger of raveling of the whipped formation at the end of the rope on the mere severing of the threads at a few points.

It will be understood that Figs. III and IV are greatly magnified and are simply schematic for the purpose of indicating the form of the stitching. Whereas about eight stitches are shown around the circumference of the rope in Fig. III, and only about five stitches are shown around the circumference in Fig. IV, it will be understood that in the normal practice of the invention a greater number of stitches will be provided. In a rope of half-inch diameter, between fifteen and twenty stitches may be provided around the rope in one revolution of the latter. In producing the effect illustrated in Fig. IV, the needle thread 16b will be first carried into the rope at the point 40 by the downward movement of the needle, the point of which will pass completely through the rope and emerge at the point 41. The loop of the needle thread which is formed below the throat-plate at the beginning of the upstroke of the needle will then be engaged by the rotary hook so that the bobbin thread 17b will in effect be passed through the needle loop. As the needle is now drawn upwardly out of the rope, the stitch setting operation, above described, takes place with the result that the interlocked portions of the needle thread and bobbin thread are drawn into the interior of the rope. At or about the same time, the feed dog becomes effective to rotate the rope slightly to bring the next stitch point 42 in line with the needle. The

same operation is then repeated as many times as required to produce the helical stitching 43 (Fig. VI) forming the desired whipping at the end of the rope. The presser bar is then lifted, as indicated above, and the threads are cut to release the rope end. A new rope end is then inserted in place and the operation is repeated.

The nature and disposition of the stitching within and around the rope is preferably such that each stitch passes through and binds together several of the strands of which the rope is formed. This insures the maintenance of the proper, twisted relation between the several strands.

The improved machine may be readily adapted for the handling of ropes of widely different size and characteristics. Ropes of slightly different diameter may be stitched with the same presser foot, but if it is desired to stitch ropes of substantially different diameters at different times, it is best to employ different presser feet, each having a groove 32 more nearly conforming with the outer contour of the rope being stitched at a particular time. It is a relatively simple matter to change from one size or form of presser foot to another by simply loosening the screw 44 (Fig. II). So also, it may be desirable to vary the pressure of the spring 25 in accordance with the character of the rope being stitched. This is accomplished by simply turning the knurled head 45 of the adjustable sleeve 26. For a relatively soft rope, a comparatively light pressure should be provided to avoid undue distortion of the rope. For a harder rope, a greater pressure is desirable to insure the proper feeding action and to prevent undesired rotation of the rope due to the off-center line of action of the needle. In dealing with softer types of rope, it is also desirable to provide the feed dog with flat surfaces 46 at the ends of the toothed projections, these flat surfaces being adapted to engage the under surface of the presser foot as the feed dog is lifted to perform its feeding action. The extent of compression and distortion of the rope may thus be definitely limited.

While an illustrative form of the invention has been described in considerable detail, it will be understood that numerous changes may be made, in the various steps to be followed and in the construction and arrangement of the several parts of the machine and in the specific form of the resulting product, without departing from the general principles and scope of the invention. The terms and expressions used herein have been used as terms of description and not of limitation.

What I claim is:

1. A machine for securing ends of rope against raveling or untwisting, comprising rope end holding means, devices cooperating with said holding means for imparting intermittent rotation to a rope end held by said means, said devices including a feed dog disposed below said holding means and movable in a direction transverse to the axis of the rope end and adapted to engage and rotate the rope end upon such movement, and stitch forming devices comprising a reciprocable needle-carrying needle bar at one side of said rope end holding means and complementary stitch forming means at the opposite side of said rope end holding means, said rope holding means being so disposed relative to the path of reciprocation of said needle that said path intersects said rope end between its axis of rotation and its periphery.

2. A machine for securing ends of rope against raveling or untwisting comprising rope end holding means, means disposed below said holding means and cooperating therewith for imparting intermittent rotation to a rope end held by said means, said cooperating means having teeth movable in a direction transverse to the axis of the rope end and adapted to engage and rotate the rope end upon such movement, multiple-thread stitch forming devices including a thread-carrying needle reciprocable in a line passing through said rope end between its axis of rotation and its periphery, complementary thread-carrying stitch forming means cooperating with said needle, and thread controlling means operative to cause the threads to be interlocked within the body of said rope end.

3. A machine for securing ends of rope against raveling or untwisting, comprising a manually releasable rope end holding means, devices cooperating with said rope end holding means for imparting intermittent rotation to a rope end held by said holding means, said devices including a feed dog disposed below said holding means and thread-carrying stitch forming devices operable to form a succession of stitches in said rope end in timed relation with said rotating means.

4. A machine for securing ends of rope against raveling or untwisting which comprises a rope end holding means, means for imparting step-by-step rotation to a rope end held by said holding means, said rotation imparting means being disposed below said holding means and having teeth movable in a direction transverse to the axis of the rope end and adapted to engage and rotate the rope end upon such movement, devices for varying the extent of each step of rotation imparted by said rotating means, and stitch forming devices constructed and arranged to form a stitch through the body of said rope end during the interval between successive increments of rotation imparted to said rope end.

5. A machine for stitching rope ends to prevent raveling or untwisting which comprises a reciprocable needle bar carrying a needle, a presser bar carrying a presser foot arranged to engage the rope end to be stitched, said presser foot having a transversely extending groove in its under surface to receive the rope end and a needle guide passage intersecting said groove transversely of the axis thereof along a line displaced from said axis, and a feed dog disposed below said presser foot and arranged to engage the rope end held by said presser foot and movable in a direction transverse to the axis of the rope end to rotate the rope end.

6. A machine for stitching rope ends to prevent raveling or untwisting which comprises a reciprocable needle bar carrying a needle, a presser bar carrying a presser foot arranged to engage the rope end to be stitched, said presser foot having a transversely extending groove in its under surface to receive the rope end and a needle guide passage intersecting said groove transversely of the axis thereof along a line displaced from said axis, and a four motion feed dog disposed below said presser foot and arranged to engage the rope end held by said presser foot to rotate the rope end, the four motions of said feed dog being in directions transverse to the axis of the rope end.

PHILIP T. MCLENDON.
